(57) **CLAIM**

The ornamental design for a transaction card as shown and described.

DESCRIPTION

FIG. 1 is a front perspective view of the transaction card showing our new design;

FIG. 2 is a front elevational view thereof;

FIG. 3 is a back elevational view of thereof;

FIG. 4 is a bottom view thereof;

FIG. 5 is a top view thereof;

FIG. 6 is a side view thereof; and,

FIG. 7 is an opposite side view thereof.

The broken lines in the drawings illustrate environmental structure on the transaction card and form no part of the claimed design.
